US0D1030050S

(12) **United States Design Patent** (10) **Patent No.:** **US D1,030,050 S**
(45) **Date of Patent:** **** Jun. 4, 2024**

(54) **SYRINGE ADAPTER FOR MEDICATION**

(71) Applicants: **James T. Doubet**, Big Horn, WY (US);
Paul D. Doubet, Farmington, IL (US)

(72) Inventors: **James T. Doubet**, Big Horn, WY (US);
Paul D. Doubet, Farmington, IL (US)

(**) Term: **15 Years**

(21) Appl. No.: **29/886,682**

(22) Filed: **Mar. 12, 2023**

Related U.S. Application Data

(60) Division of application No. 29/817,773, filed on Dec. 3, 2021, which is a division of application No. 29/737,965, filed on Jun. 12, 2020, now Pat. No. Des. 940,309, which is a division of application No. 29/710,061, filed on Oct. 20, 2019, now Pat. No. Des. 890,925, which is a continuation of application No. 16/563,896, filed on Sep. 8, 2019, now abandoned, which is a continuation-in-part of application No. 16/166,111, filed on Oct. 21, 2018, now Pat. No. 11,097,058, said application No. 29/710,061 is a continuation-in-part of application No. 16/166,111, filed on Oct. 21, 2018, now Pat. No. 11,097,058, which is a continuation-in-part of application No. 16/010,155, filed on Jun. 15, 2018, now Pat. No. 11,337,894.

CLAIM

We claim the ornamental design for a syringe adapter for medication, as shown and described.

DESCRIPTION

FIG. 1 is a perspective view of a syringe adapter, showing of our new design having a radial extension and a hexagonal element;

FIG. 2 is a front view thereof, the back view being identical thereto;

FIG. 3 is a top view thereof, the bottom view being identical thereto;

FIG. 4 is a left-side view thereof; and,

FIG. 5 is a right-side view thereof.

Features shown in the drawings using broken lines form no part of the claimed design.
